UNITED STATES PATENT OFFICE

SAMUEL EDELMAN, OF PHILADELPHIA, PENNSYLVANIA

DESIGN FOR A LAMP OR SIMILAR ARTICLE

Application filed November 26, 1929. Serial No. 33,561. Term of patent 14 years.

To all whom it may concern:

Be it known that I, SAMUEL EDELMAN, a citizen of the United States, residing at Philadelphia, county of Philadelphia, State of Pennsylvania, have invented a new, original, and ornamental Design for a Lamp or Similar Article, of which the following is a specification, reference being had to the accompanying drawing, forming a part thereof.

Figure 1 represents a front perspective view of a lamp or similar article of my new design.

I claim:

The ornamental design for a lamp or similar article as shown.

SAMUEL EDELMAN.
